UNITED STATES PATENT OFFICE.

JOHN R. WILLIAMS, OF NEWARK, NEW JERSEY, ASSIGNOR TO WILLIAM EGGERT, TRUSTEE, OF NEW YORK, N. Y.

CIGAR-WRAPPER CUTTER.

SPECIFICATION forming part of Letters Patent No. 320,199 dated June 16, 1885.

Application filed May 28, 1884. (No model.)

To all whom it may concern:

Be it known that I, JOHN R. WILLIAMS, a citizen of the United States, and a resident of Newark, in the county of Essex and State of New Jersey, have invented certain new and useful Improvements in Cigar-Wrapper Cutters, of which the following is a specification.

The invention relates to improvements in apparatus for cutting cigar or cigarette wrappers or binders wherein the leaf of tobacco or other material is held upon the cutter by air suction; and it consists, essentially, of a supporting-platen, a cutter surrounding said platen, air-spaces upon the outer edges of the cutter, and exhaust mechanism connecting with the said spaces, whereby, when a leaf of tobacco is laid upon the cutter and the exhaust mechanism is set in motion, the leaf will be held at points located outside of the cutter. That portion of the leaf within the cutter after being cut is unaffected by the air-suction, and may consequently be taken from the supporting-platen without alteration in the exhaust.

The invention which is the subject of this application will be fully described hereinafter, and is illustrated in the accompanying drawings, wherein—

Figure 1 is a top view of an apparatus embodying the invention. Fig. 2 is a central vertical transverse section of same.

In the drawings, A denotes the supporting-platen which is surrounded by a cutter, B, the latter being in the outline of a cigar or cigarette wrapper or binder. The cutter B is inclosed by a casing, C, between the inner walls of which and the vertical sides of the knife is formed the chamber D. The upper surface of the casing C is made convex, and its central portions are removed, forming a space which snugly receives the cutter B; the edges of the material surrounding said space being notched or serrated, as at a, or left plain, as at k, for the purpose of permitting the air to be exhausted downward through the chamber D.

The cutter B and casing C rest upon a base, E, of any suitable nature, which forms the bottom of the chamber D, and has an aperture, F, in which the upper end of the pipe G

is secured, the other end of said pipe being connected with suitable exhaust mechanism. In the drawings the aperture F is illustrated as being located centrally below the supporting-platen A, and leading from this aperture the base E has grooves b, which form air-connections with the chamber D on the outsides of the cutter B. The upper edges of the cutter B project slightly above the supporting-plate A and the surrounding portions of the casing C, as shown.

The parts of the apparatus being arranged as described, and the exhaust mechanism set in motion, a leaf of tobacco placed over the cutter B, with its edges upon the notches a and spaces x will be there held by suction, acting along the line of said notches and spaces, until the wrapper has been cut by means of a roller passing over the cutter or by means of a mallet, or otherwise. The wrapper after being cut from the leaf will rest on the platen A, within the edges of the cutter B, and, being unaffected by the air, may be taken from the supporting-platen at will and without danger of mutilation. After one wrapper has been cut the leaf will be readjusted over the cutter and another wrapper cut therefrom, and so on until the leaf has been consumed.

In Letters Patent numbered 297,897 and 297,898, dated April 29, 1884, and Letters Patent numbered 298,715, dated May 13, 1884, granted to me, I have described with great particularity apparatus for cutting cigar-wrappers from leaves held upon the cutter by suction, but in all of said patents the leaf is held by the action of the air upon that portion thereof located within the cutter. In said patents the platen inclosed by the cutter is in connection with the exhaust, and is used for holding the leaf. The platen embodied in the present application has no connection with the exhaust, and is employed merely for supporting the wrapper until it can be removed by hand.

What I claim as my invention, and desire to secure by Letters Patent, is—

1. The combination, with a supporting-platen, of an upwardly-extending cutter bounding the platen, a suitable casing surrounding the cutter and provided with openings on the outer side of the latter, and exhaust mech-

ism for drawing the air through said openings, substantially as set forth.

2. In an apparatus for cutting wrappers or binders for cigars or cigarettes, the supporting platea A, bounded by an upwardly-projecting cutter, B, as described, in combination with the surrounding casing C, having air-spaces, adjacent to the outer edges of the cutter, and exhaust mechanism, substantially as set forth.

Signed at New York, in the county of New York, and State of New York, this 19th day of May, A. D. 1884.

JOHN R. WILLIAMS.
